(57) **CLAIM**

The ornamental design for an bib, as shown and described.

DESCRIPTION

FIG. 1 is a front perspective view of a bib, showing a first embodiment of my new design;

FIG. 2 is a front elevational view thereof;

FIG. 3 is a rear elevational view thereof;

FIG. 4 is a right side elevational view thereof; the left side elevational view being a mirror image;

FIG. 5 is a top plan view thereof;

FIG. 6 is a bottom plan view thereof;

FIG. 7 is a front perspective view of a bib, showing a second embodiment of the design;

FIG. 8 is a front elevational view thereof;

FIG. 9 is a rear elevational view thereof;

FIG. 10 is a right side elevational view thereof; the left side elevational view being a mirror image thereof;

FIG. 11 is a top plan view thereof; and,

FIG. 12 is a bottom plan view thereof.

The broken lines in FIGS. 1-3 and 7-10 represent the portions of the design, which form no part of the claimed design.
